UNITED STATES PATENT OFFICE.

DEMUS R. RUPERT, OF HUNTINGTON, INDIANA.

RAILROAD-CROSSING SIGNAL MECHANISM.

1,418,475.

Specification of Letters Patent. Patented June 6, 1922.

Application filed May 25, 1921. Serial No. 472,376.

To all whom it may concern:

Be it known that I, DEMUS R. RUPERT, a citizen of the United States, residing at Huntington, in the county of Huntington 5 and State of Indiana, have invented certain new and useful Improvements in Railroad-Crossing Signal Mechanism; and I do hereby declare the following to be a full, clear, and exact description of the invention, such 10 as will enable others skilled in the art to which it appertains to make and use the same.

This invention relates to railroad signal mechanisms, and aims to provide a novel 15 and improved apparatus of that kind for automatically giving a danger signal or indication at a grade crossing or dangerous point of the track, when a train, street car, or other vehicle approaches the crossing or 20 signal point, and for clearing or returning the signal device after the train or car has passed such point.

Another object is the provision of a signal 25 mechanism which will be entirely automatic in operation to set and restore the signal device when the train or car approaches and leaves the crossing or danger point, to eliminate the necessity for a watchman, and to assure of a signal being given without fail, 30 thereby safeguarding life and limb and reducing railroad accidents.

A further object is the provision of a 35 novel signal stand or device to be actuated by the oncoming and passing trains or cars, and which will retain its position against accidental movement.

A still further object is the provision of 40 novel tripping devices to be operated by the wheels or other members of the trains or cars for operating the signal device or stand.

It is also the object of the invention to provide such a mechanism which is comparatively inexpensive and simple in construction, which can be readily installed, 45 which has a minimum number of parts, and which is not apt to get out of order through wear and tear.

With the foregoing and other objects in view, which will be apparent as the description 50 proceeds, the invention resides in the construction and arrangement of parts hereinafter described and claimed, it being understood that changes can be made within the scope of what is claimed without departing from the spirit of the invention.

The invention is illustrated in the accompanying drawings, wherein:—

Figure 1 is a side elevation of the mechanism, portions being broken away.

Fig. 2 is a plan view thereof.

Fig. 3 is a diametrical section of the base and turntable of the signal stand.

Fig. 4 is a plan view of the base.

The signal stand or device comprises an upright or vertical staff 7 having suitable 65 signal plates or members 8 thereon, and also preferably supporting a signal lamp 9 for use at night. The signal plates each have suitable legends and are disposed in one vertical plane, so as to be readily seen when 70 turned to a position substantially parallel with the track, whereas the signal plates are practically invisible when turned at right angles with the track so that their edges only are presented to view at the opposite 75 sides of the track. The lamp 9 signals red to the opposite side of the plates 8, and may give a white or clear signal edgewise of the plates to conform with the signals given by the plates 8 in their two positions. 80 The staff 7 is journaled between its ends in a bearing 10 supported by downwardly diverging braces 11, which can be secured at their lower ends to the ties or other support, for holding the staff upright.

The signal stand includes a turntable 12 mounted on a base 13, said turntable 12 having a central boss 14 into which the lower end of the staff is screw-threaded or otherwise secured. The base 13 has an annular upstanding flange 15 and the turntable has an annular apron 17 surrounding said flange 15, for shedding rain and water from the turntable, so as not to enter the space between the turntable and base, and to also exclude foreign matter therefrom. The base has an outstanding flange 16 to be secured on the tie or other support 21, and said base is provided thereon within the outline of the flange 15 with a sinuous seat 100 18 for an annular supporting flange 19 depending from the turntable within the base flange 15. Said flange 19 has its lower edge of sinuous form, as at 20, to seat snugly on the seat 18, and the sinuous surfaces are so 105 formed that when the staff 7 and turntable 12 are turned to position at right angles with one another, the turntable and staff are raised in moving from one position to another and settle by gravity in either posi- 110

tion, thereby maintaining the signal device in either position until turned.

The signal stand or device is operated by tripping devices including tripping levers 22 and 22' pivoted between their ends, as at 23, to one rail of the track, at one side thereof, and located suitable distances in opposite directions from the signal device or stand. These tripping levers are preferably 5 located several hundred yards from the signal stand, to assure of danger signal being given in plenty of time before the train or car approaches the crossing or protected point. The upper ends of the levers 22 and 10 22' project above the tread of the rail, to be moved one way or the other by the wheels of the train or car, and the lower arms of said levers are connected by chains or flexible elements 24 and 24', respectively, with 15 the pull wires or rods 25 and 25', which preferably extend slidably through guide tubes 26 to points adjacent to the signal stand. The adjacent ends of the wires 25 and 25' are connected by chains or flexible 20 elements 27 and 27', respectively, with studs 28 on the turntable 12, which studs are so arranged that a pull on either of the wires 25 and 25' will turn the turntable and staff 7 to move the signal device to danger position, as seen in Figs. 1 and 2. The tripping levers 22 and 22' when moved toward the signal stand by the approach of a train or car, will therefore pull the corresponding 25 chains and wires, for turning the signal device to danger position, so that said levers constitute signal setting means. Signal returning means are provided for clearing the signal, or returning same after the train or car has passed, and such means include the 30 tripping levers 29 and 29' fulcrumed or pivoted at their lower ends to the rail, as at 30, near the levers 22' and 22, respectively. Chains or flexible elements 31 and 31' are connected to the levers 29 and 29', respectively, between the ends of said levers, and are connected to the respective pull wires or rods 32 and 32' which preferably slide through guide tubes 33 and extend to points adjacent to the signal stand. The adjacent 35 ends of the wires 32 and 32' are connected by the respective chains or flexible elements 34 and 34' with the studs 28 to which the respective chains 27 and 27' are connected. When the levers 29 and 29' are swung away 40 from the signal stand, they pull the corresponding chains and wires, whereby to turn the turntable and staff back to clear position. The tripping levers 22, 22', 29 and 29' are all normally held in vertical or intermediate position by the springs 35, and when the levers 22 and 22' are swung by the wheels away from the signal stand, the respective chains 24 and 24' are simply slackened, whereas the chains 31 and 31' are 45 slackened when the levers 29 and 29', re-

spectively, are swung by the wheels toward the signal stand, the pull wires only being pulled when such levers are swung in the opposite directions from those just stated.

As shown, the tripping devices are installed at the outer side of one rail of a single track in which traffic moves in both directions. Assuming that a train or car is approaching from the left, when it reaches the tripping lever 22, the upper end of said lever is swung by the first wheel contacting with it, thereby swinging the upper end of said lever toward the signal stand, and pulling the chain 24, wire 25, and chain 27, which will turn the turntable 12 and staff 7 to swing the signal device to danger position, as illustrated in Figs. 1 and 2. The chain 24 is then slackened so that the lever 22 can oscillate by the contact of the other wheels therewith, without the interference with the signal device. When the turntable is thus turned, it rises in moving on the seat 18 of the base, and will then settle or gravitate in danger position. The wheels in passing the tripping lever 29' will simply swing said lever toward the signal stand idly, the chain 31' being slackened by such movement of the lever, without disturbing the signal device. The signal is thus automatically given by the approach of the train or car, in order that pedestrian and vehicular traffic attempting to cross the track will be forewarned. Then, when the train or car has passed the crossing or protected point, and the lever 29 is engaged by the first wheel, it is swung away from the signal stand, thereby pulling the chain 31, wire 32 and chain 34, to turn the turntable back to original position and thereby restore the signal device so that persons approaching the track may know that they can pass over in safety. When the signal device is turned to danger position, the chains 34 and 34', wires 32 and 32' and chains 31 and 31' are pulled by the turntable, so that such chains and wires are comparatively taut, so that the swinging movement of the lever 29 (or the lever 29' with traffic in the opposite direction) will result in the signal device being turned to normal clear position. After the signal device is returned to such position, the chains 31 and 31' are slackened so that the levers 29 and 29' can oscillate without disturbing the signal device. The same is true when the wheels of the train or car moving to the left pass over the lever 22', said lever being moved away from the signal stand, thereby simply slackening the chain 24'.

When traffic is moving in the opposite direction, or from the right, the lever 22' being swung toward the signal stand, will turn the signal device to danger position, and the lever 29 is operated idly, the chain 31 being slackened. When the train or car 130

reaches the lever 29' and swings it away from the stand, it will pull the signal device back to clear position, and the lever 22 being moved away from the signal stand, 5 will simply slacken the chain 24. The two sets of tripping levers thus afford means for tripping and returning the signal device by traffic moving in either direction. If traffic is only in one direction, the pair of 10 tripping levers not required can be eliminated. For double tracks, the levers 22 and 29 can be associated with the rail of one track, and the levers 22' and 29' can be used on the other track, with the same signal 15 stand, as will readily be apparent, it simply being necessary to have the signal stand located between the two tracks, and one pair of levers used on the adjacent rail of the other track.

20 The signal mechanism can not only be used at crossings, but also at other points of the track, as for example, where the view is obstructed by woods, cornfields, buildings, or the like. The mechanism also assures of 25 a danger signal being given on the approach of a train or car, and should an accident occur, and the train or car be stopped immediately, before reaching the returning tripping lever beyond the crossing, it can 30 readily be determined where the responsibility rests, and if the signal device is in danger position, where it will remain when set, unless returned intentionally, it will relieve the railroad company of responsibility 35 if the signal was ignored. Other means for producing signals than those shown can be used, for producing various suitable audible or visual signals.

The tripping devices can also be used for 40 operating the signal device for other conditions, such as at curves in the tracks to avoid the collision of trains or cars, and said tripping devices can be operated by contact wheels or members provided on the 45 locomotives or cars for that purpose, instead of being operated by the car wheels, so as to avoid the repeated vibration of said devices by the successive wheels of a train.

Having thus described the invention, what 50 is claimed as new is:—

1. A signal mechanism including a base, a turntable mounted thereon, a staff carried by the turntable and having signalling means thereon, said turntable and base having portions for raising the turntable and staff when moved from one position to another and for the gravitation thereof in either position, and means for turning said turntable to such positions.
- 60 2. A signal mechanism including a base, having a sinuous seat, a turntable having a sinuous portion bearing on said seat for raising the turntable when turned to different positions and for the gravitation of said

turntable in either position, a staff mounted 65 on the turntable and having signalling means, and means for turning said turntable to such positions.

3. A signal mechanism including a base having an annular upstanding flange and a 70 sinuous seat, a turntable having an apron surrounding said flange and a sinuous portion bearing on said base to raise the turntable when turned from one position to another and to permit the turntable to gravitate in 75 either position, a staff carried by the turntable having signalling means, and means for turning said turntable to such positions.

4. A signal mechanism including a signal 80 device, two tripping levers located in opposite directions from said device both normally in position to be operated by a passing train, and flexible connections between said levers and device arranged to operate said device from one lever to set the device 85 to signalling position, and to operate said device from the other lever, when the device is set, for returning same, such flexible connections permitting both levers when operated by a passing train to return to normal 90 position.

5. A signal mechanism including a signal device, two tripping levers located in opposite directions from said device both normally in position to be operated by a passing train, and flexible connections between 95 said levers and device and arranged so that the device is set to signalling position by one lever when swung toward said device, and to return said device by the movement 100 of the other lever away from the device, such flexible connections permitting both levers when operated by a passing train to return to normal position.

6. A signal mechanism including a signal 105 device, and tripping means located in opposite direction from said device and all normally in position to be operated by a train passing in either direction, and constructed and arranged for setting said device to signalling position by the approach of a train or car from either direction toward said device and for returning the device when the train or car has passed said device.

7. A signal mechanism including a signal 115 device, two setting tripping levers located in opposite directions from said device and normally in position to be operated by trains passing in either direction, flexible connections between said levers and device whereby 120 said levers when swung toward said device will set same to signalling position and permitting said levers to return to normal position when moved by trains passing in either direction, two returning tripping levers also 125 located in opposite directions from said device and normally in position to be operated by trains passing in either direction, and

flexible connections between the lastnamed tripping levers and said device for returning said device by the movement of said lastnamed tripping levers away from said device, and permitting the lastnamed levers to return to normal position after being operated by trains passing in either direction.

In testimony whereof I have signed my name to this specification in the presence of two subscribing witnesses.
